CONVERSION OF HYDROCARBON OILS

Lyman C. Huff, Chicago, Ill., assignor to Universal Oil Products Company, Chicago, Ill., a corporation of Delaware

Application January 19, 1935, Serial No. 2,488

11 Claims. (Cl. 196—48)

This invention particularly refers to an improved process for the selective conversion of various relatively low-boiling and high-boiling fractions of the charging stock for the process together with corresponding intermediate conversion products of the process accompanied by reduction of the residual liquid conversion products to substantially dry coke whereby to produce high yields of desirable light liquid products, such as motor fuel of good antiknock value, and minor yields of solid residue of uniformly good quality.

The present invention is particularly well adapted to the treatment of hydrocarbon oils of relatively wide boiling range such as crude petroleum, topped crude and the like although it is also advantageous as applied to the treatment of either low-boiling or relatively high-boiling oils.

When employed for the treatment of oils of relatively wide boiling range, charging stock is preferably separated, together with the intermediate conversion products of the process, into selected relatively high-boiling, intermediate and low-boiling fractions. The high-boiling fractions are subjected to conversion conditions of elevated temperature and superatmospheric pressure in a heating coil and the resulting heated products are introduced into a coking chamber, preferably operated at a relatively low superatmospheric pressure, wherein their high-boiling components are reduced to coke. Vaporous products are withdrawn from the coking zone and any high-boiling components, such as tars and similar high coke-forming materials, are separated therefrom and returned to the coking chamber while the remaining vaporous products are subjected to fractionation. The intermediate fractions of the charging stock and reflux condensate are subjected to independently controlled conversion conditions of elevated temperature and superatmospheric pressure in a separate heating coil and communicating reaction chamber, the resulting vaporous and liquid conversion products separated, the latter supplied to the coking chamber, wherein they are reduced to coke, and the vaporous conversion products are supplied to said fractionation together with the aforementioned remaining vaporous products from the coking operation. The relatively low-boiling fractions of the charging stock and reflux condensate are subjected to independently controlled conversion conditions of elevated temperature and superatmospheric pressure in another separate heating coil, preferably of the type wherein the oil is heated to the desired conver-

sion temperature and then maintained at or near the maximum conversion temperature attained for a predetermined time, and all or a regulated portion of the highly heated products from the last mentioned heating coil are introduced into the coking chamber to commingle therein with the materials undergoing coking and supply additional heat thereto to assist their reduction to coke. The intermediate conversion products of the process separated into said selected relatively low-boiling, intermediate and high-boiling fractions comprise the reflux condensate formed by said fractionation of the vaporous products of the process and fractionated vapors of the desired end-boiling point are subjected to condensation to form the desired final light distillate product of the process, preferably comprising motor fuel of high antiknock value.

The accompanying diagrammatic drawing illustrates one specific form of apparatus in which the process may be accomplished.

Referring to the drawing, heating coil 1 is located within a furnace 2, of any suitable form, by means of which the oil supplied thereto, in the manner to be later described, is subjected to the desired conversion conditions of elevated temperature and superatmospheric pressure and the heated products are discharged from the heating coil through line 3 and valve 4 into reaction chamber 5.

Chamber 5 is also preferably maintained at a substantial superatmospheric pressure and, although not indicated in the drawing, is preferably insulated to minimize the loss of heat therefrom by radiation. Conversion of the heated products from heating coil 1, and particularly their vaporous components, continues in the reaction chamber and, in the particular case here illustrated, the resulting vaporous and liquid conversion products are separated in this zone.

Liquid conversion products may be withdrawn from the lower portion of chamber 5 through line 6 and valve 7, either alone or together with a minor portion of the vaporous conversion products from this zone, and are directed through lines 8 and 8' controlled by the respective valves 9 and 9' into the respective coking chambers 10 and 10' wherein they are reduced to substantially dry coke, as will be later more fully described.

Vaporous products evolved in coking chambers 10 and 10' as well as any vaporous conversion products supplied, as such, to the coking chambers, as will be later more fully described, are withdrawn from chambers 10 and 10' through 55

the respective lines 11 and 11' controlled, respectively, by valves 12 and 12' and are directed through line 13 into separating chamber 14. Vaporous conversion products separately withdrawn from reaction chamber 5 at any desired point in this zone may also be directed through line 15 and valve 16 into separating chamber 14 also at any desired point.

Chamber 14 is preferably operated at a substantially reduced pressure relative to that employed in the reaction chamber and the materials supplied to this zone, as previously described, from the coking chambers and, when desired, from the reaction chamber are substantially freed in this zone of any high-boiling components or entrained heavy liquids such as tars and similar high coke-forming materials unsuitable for further conversion in any of the various heating coils of the system. Liquid products removed from the materials supplied to chamber 14 are withdrawn from the lower portion of this zone through line 17 and valve 18 to pump 19 by means of which they are returned through line 20, valve 21, line 6 and lines 8 and 8' controlled by the respective valves 9 and 9' to coking chambers 10 and 10', respectively, for further treatment and reduction to coke. The resulting vapors are withdrawn from the upper portion of chamber 14 through line 22 and valve 23 to fractionation in fractionator 24.

The insufficiently converted components of the vaporous products supplied to fractionator 24 are condensed in this zone as reflux condensate which in turn is separated by fractional distillation into selected relatively low-boiling, intermediate and high-boiling fractions each of which are subjected to independently controlled conversion conditions within the same system, as will be presently described in more detail. Fractionated vapors of the desired end-boiling point are withdrawn, together with uncondensable gas produced by the process, from the upper portion of fractionator 24 through line 25 and valve 26 and are subjected to condensation and cooling in condenser 21. The resulting distillate and gas passes through line 28 and valve 29 to collection and separation in receiver 30. Uncondensable gas may be released from the receiver through line 31 and valve 32. Distillate may be withdrawn from receiver 30 through line 33 and valve 34 to storage or to any desired further treatment.

The selected high-boiling fractions of the reflux condensate formed in fractionator 24, preferably comprising materials such as fuel oil, heavy gas oil and the like, are withdrawn from the lower portion of this zone through line 35 and valve 36 to pump 37 by means of which they are directed through line 38 and valve 39 to heating coil 40, wherein they are subjected to further conversion. The required heat is supplied to the oil passing through heating coil 40 to subject it to the desired conversion conditions of elevated temperature and superatmospheric pressure by means of a furnace 41 of any suitable form and the heated products are discharged from heating coil 40 through line 42 and valve 43 and are introduced into coking chambers 10 and 10' through the respective lines 44 and 44' controlled respectively by valves 45 and 45'.

The selected intermediate fractions of the reflux condensate formed in fractionator 24, preferably comprising materials such as gas oil and the like may be withdrawn from a suitable intermediate point in this zone, such as, for example, through line 46 and valve 47, by means of

which they are supplied to pump 48. The oil thus supplied to pump 48 is directed therefrom through line 49 and valve 50 to conversion in heating coil 1, in the manner previously described.

The selected low-boiling fractions of the reflux condensate formed in fractionator 24 preferably comprising such materials as pressure distillate bottoms, kerosene or kerosene distillate and the like and including, when desired, any high-boiling motor fuel fractions of inferior antiknock value, are withdrawn from any suitable point in the upper portion of the fractionator and supplied, for example, through line 51 and valve 52 to pump 53 by means of which they are fed through line 54 and valve 55 to heating coil 56 for further conversion.

Heating coil 56 is located within a furnace 57 of any suitable form and preferably comprises a heating coil of the type wherein the oil supplied thereto is heated to or near the maximum desired conversion temperature and then maintained at a substantially constant temperature approaching the maximum attained for a predetermined time. The furnace illustrated is of the "double end-fired" type which permits independent control of the heating conditions about different portions of the heating coil whereby a heating curve of the desired type may be readily obtained. The stream of highly heated products is discharged from heating coil 56 through line 58 and valve 59 and may be supplied, in part, through line 62 and valve 63 into separating chamber 14. However, a regulated portion, at least, of the heated products from heating coil 56 is preferably introduced into coking chambers 10 and 10' through lines 60 and 60' respectively, controlled by the respective valves 61 and 61' wherein the highly heated products are directly commingled with the materials undergoing coking and supply additional heat thereto for the purpose of assisting their reduction to coke.

Coking chambers 10 and 10' are similar zones, preferably operated at a substantially reduced pressure relative to that employed in reaction chamber 5, wherein reduction of the residual liquid conversion products of the process to coke is accomplished. It will be understood, of course, that only one coking chamber or any desired number of such zones may be employed, although two are illustrated in the drawing. Coke may be allowed to accumulate within the coking chamber until it is substantially filled following which it may be cooled, cleaned and prepared for further operation in any well known manner, not illustrated. When a plurality of coking chambers is employed the chambers preferably are alternately operated, cleaned and prepared for further operation in order that the coking stage, in common with the rest of the process, may be operated continuously. Chambers 10 and 10' are provided with suitable drain-lines 82 and 82' respectively, controlled by the respective valves 83 and 83' which may also serve as a means of introducing steam, water or any other suitable cooling medium into the chamber after its operation is completed and after it has been isolated from the rest of the system, in order to hasten cooling and facilitate the removal of coke therefrom.

Hydrocarbon oil charging stock for the system is supplied, in the case here illustrated, through line 64 and valve 65 to pump 66 by means of which it is fed through line 67.

When the charging stock comprises an oil of relatively wide boiling range which, however, does

not contain any appreciable quantity of high-boiling materials unsuitable for conversion in heating coil 48 it is preferably directed, all or in part, from line 87 through line 88 and valve 89 into fractionator 24, wherein it is subjected to vaporization and fractional distillation together with the vaporous conversion products supplied to this zone, whereby it may be separated, together with the reflux condensate, into selected relatively low-boiling, intermediate and high-boiling fractions for selective conversion, in the manner already described. It is, of course, within the scope of the invention to supply a regulated portion or all of the charging stock to fractionator 24 regardless of its characteristics so long as it does not contain any appreciable quantity of materials of a high coke-forming nature unsuitable for conversion in heating coil 48 and does not contain any appreciable quantity of motor fuel or motor fuel fractions of inferior quality which will contaminate the overhead vaporous product from the fractionator.

When the charging stock consists of or contains an appreciable quantity of high-boiling materials unsuitable for conversion in heating coil 48 it is preferably directed from line 87 through lines 78 and 71, valve 72, line 78 and valve 79 into vaporizing chamber 14, wherein its high-boiling components remaining unvaporized in this zone may commingle with the heavy liquid conversion products supplied from this zone, as previously described, to the coking zone, while any lower boiling vaporous components of the charging stock pass, together with the vaporous conversion products from chamber 14, to fractionation in fractionator 24, in the manner previously described.

All or a regulated portion of the charging stock may be supplied to chamber 14, in the manner described, regardless of its characteristics, serving as a cooling and refluxing medium in this zone and preferably when employed for this purpose it is introduced, as indicated in the drawing, into the upper portion of the chamber and allowed to flow downward therethrough.

A regulated portion of the high-boiling fractions of the reflux condensate, either alone or admixed with any corresponding components of the charging stock, supplied, as previously described, to fractionator 24, may be utilized, separately or in conjunction with a portion or all of the charging stock not supplied to the fractionator, as a cooling and refluxing medium in chamber 14. This may be accomplished by diverting regulated quantities of the high-boiling fractions of the reflux condensate from line 88 through line 89, valve 81 and line 78, preferably into the upper portion of chamber 14.

It will be understood that the invention is not limited to the specific form of apparatus illustrated nor to the specific process described.

The preferred range of operating conditions which may be employed to accomplish the objects of the present invention, in an apparatus of the character illustrated and above described, may be approximately as follows: The light oil heating coil to which low-boiling fractions of the reflux condensate are supplied for conversion or reforming, either alone or together with charging stock or low-boiling fractions thereof, preferably employs an outlet conversion temperature of the order of 950 to 1,100° F., preferably with a superatmospheric pressure measured at this point in the system which may range, for example, from 300 to 1,000 pounds, or thereabouts, per square

inch. As previously indicated, the final stages of this heating coil preferably comprise the "soaking" section wherein the oil previously heated to or near the maximum desired conversion temperature is maintained at a substantially constant 5 temperature, near the maximum, for a predetermined time. The heavy oil heating coil wherein high-boiling fractions of the reflux condensate are subjected to conversion, either alone or together with high-boiling charging stock or high-boiling fractions of the charging stock, may employ an outlet conversion temperature ranging, for example, from 800 to 950° F., preferably with a superatmospheric pressure measured at the outlet from the heating coil of from 100 to 500 15 pounds, or more, per square inch. The heating coil to which intermediate fractions of the reflux condensate are supplied for conversion, either alone or together with charging stock or charging stock fractions of corresponding characteristics, may employ an outlet conversion temperature of from 900 to 1,000° F., preferably with a superatmospheric pressure at this point in the system of the order of 200 to 800 pounds, or thereabouts, per square inch. The reaction 25 chamber succeeding the last mentioned heating coil preferably employs a substantial superatmospheric pressure, which may be substantially the same or somewhat lower than that employed in the preceding heating coil. The coking chambers 30 are preferably operated at a substantially reduced pressure relative to that employed in the reaction chamber ranging, for example, from 100 pounds, or thereabouts, per square inch, down to substantially atmospheric pressure. The separating 35 chamber to which vaporous products from the coking chamber are supplied preferably employs substantially the same or somewhat lower pressure than that utilized in the coking zone. The fractionating, condensing and collecting portions 40 of the system may employ pressures substantially the same or somewhat lower than that employed in the separating chamber.

As a specific example of one of the many possible operations of the process of the present invention as it may be accomplished in an apparatus such as illustrated and above described, the charging stock is an 18° A. P. I. gravity Mid-Continent fuel oil which is supplied, in part, to the fractionator and, in part, to the separating chamber preceding the fractionator. High-boiling fractions of the charging stock and of the reflux condensate formed in the fractionator are subjected in the heating coil to which they are supplied to an outlet temperature of approximately 45 900° F. at a superatmospheric pressure of about 200 pounds per square inch and the heated products are introduced into alternately operated coking chambers maintained at a superatmospheric pressure of about 50 pounds per square 50 inch. Intermediate fractions of the charging stock and reflux condensate are subjected in a separate heating coil to an outlet conversion temperature of approximately 950° F., at a superatmospheric pressure of about 400 pounds per square 55 inch. This pressure is substantially equalized in the succeeding reaction chamber wherein vaporous and liquid conversion products are separated, the latter being supplied direct to the coking chambers while the vaporous products are supplied, together with vaporous products from the coking chamber, to the separating chamber which is maintained at a superatmospheric pressure of approximately 40 pounds per square inch. Heavy 60 liquid products recovered in the separating chamber 70

ber are also returned to the coking chambers and the vaporous products from the separating chamber are subjected to fractionation for the formation of said reflux condensate. The low-boiling fractions of the reflux condensate having a boiling range of approximately 350 to 550° F. are heated in a separate heating coil to a conversion temperature of approximately 975° F. and are then maintained for a predetermined time in the soaking section of the heating coil at a substantially constant temperature which does not exceed approximately 1020° F. The pressure employed at the outlet from this heating coil is approximately 800 pounds per square inch. The stream of highly heated products from this zone are introduced into the coking zone and directly commingled therein with the materials undergoing coking. This operation may produce, per barrel of charging stock, approximately 60 percent of 400° F. end-point motor fuel having an octane number of approximately 70 by the motor method and approximately 100 pounds of low volatile coke of uniformly good quality and structural strength, the remainder being chargeable, principally, to 25 uncondensable gas.

I claim as my invention:

1. In a process for the conversion of hydrocarbon oils wherein an oil is subjected to conversion conditions of elevated temperature and superatmospheric pressure in a heating coil, the heated products introduced into an enlarged reaction chamber, also maintained at superatmospheric pressure, wherein particularly their vaporous components are subjected to appreciable continued conversion and wherein separation of vaporous and liquid conversion products is accomplished, the vaporous and liquid conversion products separately withdrawn from the reaction chamber, the vaporous conversion products subjected to fractionation whereby their insufficiently converted components are condensed, fractionated vapors of the desired end-boiling point subjected to condensation and the resulting distillate collected, the improvement which comprises separating a relatively light reflux condensate and a relatively heavy reflux condensate from the vaporous products of the process undergoing said fractionation, returning the light reflux condensate to the heating coil for further conversion, subjecting the heavy reflux condensate to independently controlled conversion conditions of elevated temperature and superatmospheric pressure in a separate heating coil, introducing the heated products from said separate heating coil into a coking chamber, withdrawing liquid conversion products from the reaction chamber and introducing the same into said coking chamber, supplying vapors from the coking chamber to a separating chamber wherein undesirable high-boiling components, including any entrained high coke-forming liquids, are removed therefrom, returning the liquid products from said separating chamber to the coking chamber and subjecting vaporous products from the separating chamber to said fractionation.
2. A process of the character defined in claim 1 wherein charging stock for the process, comprising hydrocarbon oil of relatively wide boiling range is separated into selected relatively low-boiling and high boiling fractions which are subjected, respectively, to conversion together with said selected relatively low-boiling and high-boiling fractions of the reflux condensate.
3. In a process for the conversion of hydrocarbon oils wherein an oil is subjected to conversion conditions of elevated temperature and superatmospheric pressure in a heating coil, the

heated products introduced into an enlarged reaction chamber, also maintained at superatmospheric pressure, wherein particularly their vaporous components are subjected to appreciable continued conversion and wherein separation of 5 vaporous and liquid conversion products is accomplished, the vaporous conversion products subjected to fractionation whereby their insufficiently converted components are condensed as reflux condensate, fractionated vapors of the desired end-boiling point subjected to condensation and the resulting distillate collected, the improvement which comprises separating the reflux condensate formed by said fractionation of the vaporous products of the process into selected 10 relatively low-boiling, intermediate and high-boiling fractions, returning intermediate fractions of said reflux condensate to the heating coil for further conversion, subjecting high-boiling fractions of the reflux condensate to independently 15 controlled conversion conditions of elevated temperature and superatmospheric pressure in a separate heating coil, introducing the resulting heated products into a coking chamber, withdrawing liquid conversion products from the reaction chamber and introducing the same into the coking chamber, supplying vaporous products from the coking chamber to a separating chamber wherein undesirable high-boiling components, including entrained high coke-forming liquids and 20 the like are removed therefrom, returning said undesirable high-boiling materials to the coking chamber, subjecting selected low-boiling fractions of said reflux condensate to independently controlled conversion conditions of elevated 25 temperature and superatmospheric pressure in another separate heating coil, introducing regulated portions of the highly heated products from the last mentioned heating coil into the coking chamber, supplying the remainder of said highly heated products from the last mentioned heating coil to said separating chamber and subjecting vaporous products remaining uncondensed in said separating chamber to said fractionation.

4. A process of the character defined in claim 3 wherein charging stock for the process, comprising hydrocarbon oil of relatively wide boiling range, is separated into selected fractions and wherein fractions of the charging stock corresponding to said selected fractions of the reflux condensate are subjected to conversion therewith.

5. A process of the character defined in claim 3 wherein hydrocarbon oil charging stock for the process is supplied, at least in part, to the fractionating stage of the system.

6. A process of the character defined in claim 3 wherein hydrocarbon oil charging stock for the process is supplied, at least in part, to said separating chamber.

7. The process as defined in claim 3 further characterized in that hydrocarbon oil charging stock for the process is supplied in separate portions to the fractionating stage of the system and to said separating chamber.

8. A hydrocarbon oil conversion process which 65 comprises fractionating hydrocarbon vapors, formed as hereinafter set forth, to separate relatively heavy, intermediate and light reflux condensates therefrom, heating the heavy reflux condensate to cracking temperature under pressure in a heating coil and then discharging the same into a coking zone, subjecting the intermediate reflux condensate to independently controlled cracking conditions of temperature and pressure in a second heating coil and separating 75

- resultant vapors from unvaporized oil in an enlarged reaction zone, separately removing vapors and unvaporized oil from the reaction zone and introducing the latter to the coking zone, distilling the heated heavy reflux condensate and the unvaporized oil to coke in the coking zone, subjecting the light reflux condensate in a third heating coil to more drastic cracking than the heavy and intermediate reflux condensates, discharging heated products from said third coil into the coking zone to assist the coking operation therein, supplying vapors from the coking zone and from the reaction zone to the fractionating step, and finally condensing the fractionated vapors.
- 15 9. The process as defined in claim 8 further characterized in that heavy coke-forming components are separated from the vapors from the coking zone prior to the fractionation of these vapors and such separated heavy components re-20 turned to the coking zone.
10. A hydrocarbon oil conversion process which comprises fractionating hydrocarbon vapors, formed as hereinbefore set forth, to separate relatively heavy, intermediate and light reflux condensates therefrom, heating the heavy reflux condensate to cracking temperature under pressure in a heating coil and then discharging the same into a coking zone, subjecting the inter-25 mediate reflux condensate to independently controlled cracking conditions of temperature and pressure in a second heating coil and separating resultant vapors from unvaporized oil in an enlarged reaction zone, separately removing vapors and unvaporized oil from the reaction zone and introducing the latter to the coking zone, distilling the heated heavy reflux condensate and the unvaporized oil to coke in the coking zone, subjecting the light reflux condensate in a third heating coil to more drastic cracking than the heavy and intermediate reflux condensates, discharging heated products from said third coil into the coking zone to assist the coking operation therein, introducing the vapors from the coking and re-action zones into a contacting zone and therein contacting the same with fresh charging oil for the process, thereby separating heavy components of the vapors and vaporizing the charging oil at least in part, supplying the commingled vapors from the contacting zone to the fractionating step, and finally condensing the fractionated vapors.
11. The process as defined in claim 10 further characterized in that liquid products separated in the contacting zone are introduced to the coking zone.

LYMAN C. HUFF.
